(57) **CLAIM**

We claim the ornamental design for a television with rollable display, as shown and described.

DESCRIPTION

FIG. 1 is a front perspective view of a television with rollable display showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a rear perspective view thereof;

FIG. 9 is a front perspective view of the television with rollable display of FIG. 1 shown in a first alternate position in which the rollable display is accommodated in a lower drawer thereof and is halfway rolled up;

FIG. 10 is a front perspective view of the television with rollable display of FIG. 1 shown in a second alternate position in which the rollable display is accommodated in an upper drawer thereof and is halfway rolled down;

FIG. 11 is a front perspective view of the television with rollable display of FIG. 1 shown in a third alternate position in which the upper drawer is opened and the rollable display is accommodated in the lower drawer and is halfway rolled up; and,

FIG. 12 is a front perspective view of the television with rollable display of FIG. 1 shown in a fourth alternate
